TELEVISION ANTENNA

Harvey R. Brandt and Nicholas Werner, Somerville, N.J.,
assignors to Gaven Electronics Division Antennacraft
Company

Filed Nov. 15, 1972, Ser. No. 306,798

Term of patent 14 years

Int. Cl. D14—03

U.S. Cl. D26—14 F

Fig. 3

FIG. 1 is a perspective view of a television antenna showing our new design;

FIG. 2 is one side view thereof, the other side view being substantially identical;

FIG. 3 is a top plan view thereof;

FIG. 4 is a front view thereof; and

FIG. 5 is a rear view thereof.

We claim:

The ornamental design for a television antenna, as shown and described.
